UNITED STATES PATENT OFFICE.

JOSEPH GASSER, OF TRENTON, NEW JERSEY.

BRUSH.

1,340,040.

Specification of Letters Patent. Patented May 11, 1920.

Application filed August 23, 1918. Serial No. 251,167.

To all whom it may concern:

Be it known that I, JOSEPH GASSER, a citizen of United States, residing at 27 Carroll street, Trenton, in the county of Mercer and State of New Jersey, have invented new and useful Improvements in Brushes, of which the following is a specification.

The invention relates to brushing and scrubbing, and more particularly to a device for accomplishing that purpose, and has for an object to provide a rotary brush for use in brushing or scrubbing, and which is particularly adapted for use in cleaning or scrubbing rust from iron or steel.

10 Although the invention may be adapted for various purposes, I particularly employ my brush for use on the hulls of ships and the like, for removing therefrom any accumulated rust, barnacles, or other foreign 20 matter. To this end I provide a brush body which is preferably arranged with steel bristles, and which is rotated at a high rate of speed, in order to effectively remove any incrustations that may have accumulated on 25 the sides of a ship or on steel plates.

In the further disclosure of the invention, reference is to be had to the accompanying drawing, constituting a part of this specification, in which similar characters of 30 reference denote corresponding parts in all the views, and in which—

Figure 1 is a side elevation of the brush.
Fig. 2 is an end view.

Fig. 3 is a vertical longitudinal sectional view taken on the line 3—3 in Fig. 2, and
35 Fig. 4 is a cross-sectional view taken on the line 4—4 in Fig. 1.

Referring more particularly to the views, the brush indicated in its entirety by the 40 numeral 10, consists essentially of a frame 11, including a casing 12 having a suitable motor 13, seated therein, a handle 14 being provided with a shank 15 having connection between the handle and the casing, and 45 constituting a part of the frame 11. In the event the motor 13 is an electrical motor, the necessary wires 16 are carried along the shank 15 through the handle 14, with a suitable switch 17 at a convenient place on the 50 handle, the wires 16 then being carried to a suitable source of electrical energy. Of course it will be understood that I may employ some other form of motor, such as an air-driven motor and supply air by means 55 of a suitable pipe or tube (not shown) and which may be carried through the handle

and shank in the same manner as the wires 16. The casing 12 at one end thereof is provided with an opening 18, and immediately adjacent the opening within the casing, is 60 disposed one end of the shaft 19 of the motor 13. A brush body 20 consisting of a substantially cylindrical element 21 and bristles 22 secured therein, is disposed so that the body or main part will encircle the 65 motor casing, and the brush body is provided with an indented portion 23, in the nature of a bearing and which has an opening 24, through which extends the shaft 19 of the motor, a suitable thumb nut 25 being 70 arranged in the indented portion to engage with the shaft and rigidly clamp the brush body to the motor shaft. With this construction it will be seen that the brush body will in fact be mounted upon the casing as 75 a bearing or support, and will have connection with the shaft of the motor through the medium of the body 21 and thumb nut 25.

Adjacent the inner end of the handle 14 there is provided a shield 26, which is substantially semi-circular in shape and which is suitably secured to the shank 15 to partially encircle the brush body, thus protecting the hand of the operator, which will be clearly seen.

In order that the free end of the brush body, or namely, that part which is nearest to the inner end of the casing, will not bear against the exterior of the casing in the rapid rotation of the brush body, I provide 90 a ring 27, which secured to the inner end of the brush body, tends to aid in properly supporting the brush body upon the casing, and thereby prevents any undue friction of the main part 21 of the brush body with the 95 casing.

With a brush of the character described, it will be clear that the part of the brush opposed to the shield can be brought to bear against the side of a steel plate or the hull of 100 a vessel, and when the switch 17 is operated to close the circuit to the motor, in the event that an electrical motor is employed, the rotation imparted to the brush body will cause the bristles to operate upon the incrustations on the steel plate, and aid in removing the same.

As mentioned heretofore, the device described is adapted for removing rust or other accumulations on various kinds of 110 plates or the sides of vessels, and it will be seen that the machine is a very simple con-

struction; consisting of few parts that cannot readily get out of order; can be readily operated with one hand, and aside from protecting the operator and his hand by employment of a shield, can be readily positioned at various angles and conveniently held to accomplish the desired result.

I claim:

A brush holder comprising a frame, a motor casing carried by the frame and rigid with the latter, said motor casing projecting

from one side of the frame, a handle on the frame, a brush body loosely encircling the casing and disposed to one side of the frame, and a segmental shield interposed between the handle and the brush body, said handle being disposed in offset relation to the frame, and lying in the central transverse plane of said casing, brush body and said shield.

In testimony whereof I affix my signature.

JOSEPH GASSE.
